UNITED STATES PATENT OFFICE.

ASA FARRAR, OF JACKSONVILLE, FLORIDA.

SAFETY ATTACHMENT FOR SWITCH-STANDS.

1,197,020.

Specification of Letters Patent. Patented Sept. 5, 1916.

Application filed January 6, 1916. Serial No. 70,686.

To all whom it may concern:

Be it known that I, ASA FARRAR, a citizen of the United States, residing at Jacksonville, in the county of Duval and State of Florida, have invented certain new and useful Improvements in Safety Attachments for Switch-Stands, of which the following is a specification.

My invention relates to an improvement in safety-attachments for switch-stands, the object being to provide a locking device by which each workman is provided with a means of controlling it, so that the switch cannot be turned until every workman provided with this means of protection has had his part in releasing the lock of the switch. Many accidents have occurred which have caused workmen either severe injury or death, due to the opening of a switch and the train or locomotive colliding with the car or cars on the siding, on which men have been working, or in which they have been living; and this invention has been devised to preclude the possibility of any such accidents.

With these objects in view, my invention comprises two bars pivoted together and constructed for attachment to a switch. This attachment is adapted to receive individual locks carried by each workman having anything to do with a car on the siding or switch. Each lock has an individual number, and the workman has a key for his own lock which will fit his lock only, and a record of which is kept at the railroad office. So it is within the power of each workman so provided to protect himself, as provision is made for any number of these locks to be applied to the attachment, making it impossible for the switch to be turned until the last lock has been removed. The office keeps account of each lock (by number) and the workman who carries it, each workman being supplied as he goes on a job, and turning in his lock and key when he leaves the employ of the railroad company.

The invention further consists in certain novel features of construction and combinations of parts, which will be hereinafter described and pointed out in the claims.

In the accompanying drawings:—Figure 1 shows the attachment applied to a switch; Fig. 2 is an enlarged view in perspective; Fig. 3 shows the attachment wide open; and Fig. 4 is a transverse sectional view.

A and B are two plates, the former of which is folded into U-shape in cross-section, it being adapted to fit, receive and inclose the plate B. The pin 1 pivotally connects the plates together at one end, and a clevis 2 is connected with the pin to receive the chain 3 by which it is attached to the switch-stand 4. The pivoted end of plate B is rounded off at one corner, and the opposite corner is adapted to engage the inner wall of the U-shaped plate B when the attachment is swung open, (as shown in Fig. 3) when the two plates are approximately at right-angles or capable of swinging substantially at right-angles to each other.

Plate B has a hook 6 on its free end adapted to receive the staple of the switch, and this hook is closed and housed by the U-shaped member when the plates are in their normal position.

A plurality of holes 7, 7, are formed through both plates, and these are brought into registry when the attachment is in its closed or locked position. Numbered padlocks 8, 8, are inserted through these holes and fastened to hold the attachment on the switch. These padlocks are each given a different number, and as the keys are necessarily all different, there is a correspondingly-numbered key which fits each lock. Each workman on a siding or switch, who would be interested in the locking of a switch, is provided with a padlock and key, for which he is responsible, and which is his means of protection against accident. When he goes to work, the first thing he does is to fasten his lock in one of the holes in the plates A and B, where it must remain until he himself unlocks it. There may be one, or a dozen, or as high as fifty or one hundred workmen interested, and each one places his lock in the attachment, so that the last one to remove his lock is always protected, as the switch cannot be thrown until the last lock has been removed. Thus a means of safety for each individual workman is provided, so that he is not dependent on any of his fellows to insure his safety. In this way, not only is protection afforded for the life and limb of the employee, but also the employer has an effectual means of protection against responsibility and damage-suits, as the workman himself has within his own control the means for his safety.

One of the holes 8' and plates A and B might be large enough to accommodate the

regular standard switch-lock in the event that it is found desirable to use the attachment on regular siding switches and to keep it locked with the regular switch-lock, thus 5 permitting the use of the individual locks by the workmen just the same without the necessity of removing the regular switch-lock.

In nearly all switch-stands, the staple for 10 the switch-lock is of sufficient size to permit the use of the attachment in the staple when the switch-lock is already through the staple; but as some switch-stands are fitted with very small switch staples, which would 15 not permit of the hook of the attachment in addition to the lock already through the staple, by making provision in the attachment for one hole large enough for the regular switch-lock to be used, it would over- 20 come any difficulty in using the attachment at any point, and would make it practicable to use the attachment on a line of road-switches as well as in shop and repair yards.

I claim:

25 1. A switch-attachment comprising two plates having registering holes and adapted to be attached to a switch, and individual locks adapted to be fastened in said holes whereby to hold the plates together upon 30 the switch and to make it impossible for the attachment to be removed from the switch until the last lock shall have been unfastened.

2. A switch-attachment comprising two plates pivotally connected together at one end and having holes adapted to register with each other, one plate having a hook at one end, and the other plate adapted to close said hook when the holes of the plates are in registry, and individual locks adapted to be fastened in said registered holes whereby each workman provided with a lock is afforded his own means of safety and the plates are held together until the last lock shall have been removed therefrom. 35 40 45

3. An attachment for switches comprising two perforated plates pivoted together, one U-shaped in cross-section, and the other flat and provided with a hook at the free end, which is closed by the U-shaped plate 50 when the two plates are in normal position and the holes are in registry, and locks adapted to be inserted in the holes, each lock adapted to be in the possession and control of a workman, whereby the attachment cannot be released from the switch until every lock has been removed therefrom. 55

4. A switch attachment comprising two members hingedly connected at one end and one having a hook adapted to be ensheathed in the other, both having a plurality of registering holes to removably receive individually controlled locking means. 60

In testimony whereof I affix my signature.

ASA FARRAR.
